PARTITION CONSTRUCTION

Wilmot C. Douglas, Plainfield, N. J., assignor to
 The Celotex Corporation, Chicago, Ill., a corporation of Delaware

Application April 16, 1938, Serial No. 202,565

10 Claims. (Cl. 189—84)

This invention relates to partitions for buildings and has for its object to provide a construction simple in parts, strong, easy to erect and therefore more efficient and practical than those 5 heretofore proposed.

With these and other objects in view the invention resides in the novel details of construction and combinations of parts as will be disclosed more fully hereinafter and particularly 10 pointed out in the claims.

Referring to the accompanying drawing forming 15 a part of this specification and in which like numerals designate like parts in all of the views—

Figure 1 is a foreshortened elevational view of 20 a partition to which this invention has been applied; and

Figure 2 is a horizontal sectional view of the 25 partition taken as on the line 2—2 thereof and looking in the direction of the arrows.

This invention is directed to the formation of 30 a partition or wall upon vertical metallic building structures in the nature of studding, the partition consisting of a plurality of relatively thin yet strong panels comprising the wall surface 35 mounted within the angles of the metallic framing or steel members, said panels arranged in horizontal rows, one row above another, as usual. That is to say, the metallic members may be relatively heavy framing members carrying a considerable weight of the building, or they may be 40 relatively light structural members intended solely for the support of the partition. Further, the metallic members may be of various cross-sectional shapes, though possibly the cheapest 45 efficient member will be the ordinary angle bar shown in the drawing. The panels may be of any character suitable for partition forming and therefore this invention contemplates the use of any and all of the known wall-boards, plasterboards, composition boards, fiber boards, whether 50 reinforced or not, decorated or undecorated, as well as other objects used for wall construction including wood strips, bricks, tiles, glazing in sheets or bricks, metal plates, etc.

In the drawing 1 and 2 indicate a pair of vertically disposed angle bars arranged to form a T but having their adjoining flanges 3 and 4 spaced apart by an interposed coextensive separating and anchoring strip 5 adapted to receive 55 and hold nails, a plurality of spaced bolts such as 6 or other suitable fasteners securing said strip and said bars together. It will be understood that the bars will extend vertically in accordance with the height of the partition and have their tops and bottoms secured to any suit-

able cross support, and that the bolts 6 will be provided at suitable spacings throughout the length of the bars. Bolts are to be preferred because of the similarity of thickness of the heads and nuts thereof so that, when the bolts are in place as shown, the heads and nuts thereof will serve as substantially equal spacing means for separating the ends of the panels such as 7 and 8 from the bar flanges 3 and 4.

The bars 1 and 2 constituting one vertical 10 metallic supporting unit, have duplications constituting other supporting units, all of said units spaced from each other in accordance with the 15 sidewise extent of the panels, and such a duplication is shown at 11 and 12. Likewise the parts 13, 14, 15 and 16 have their duplicates 18, 19, 20 and 21 in each of such units, and it will be understood 20 that all of such units will be aligned as indicated in the drawing to accommodate the ends of the panels. Therefore, the unit composed of the bars 1 and 2 will receive in its respective angles the 25 ends of the panels such as 7 and 8, and the next adjacent unit composed of the bars 11 and 12 will receive in its respective angles the other end of the panel 8 and the end of the next following panel such as 16, and so on in like manner throughout the horizontal dimension of the partition.

To retain the panels 7 and 8 in place, a vertically extending batten strip 17 is applied so as to 30 overlap the end edges of said panels, the batten strip being secured to the supporting unit as by a plurality of nails 18 driven therethrough and into the separating strip 5, the securing of the batten strip causing the rear faces of said 35 panels to contact the surfaces of the rear flanges 1 and 2 of the angle bars, as readily understood. The batten strip may be of any suitable material and exterior appearance but preferably has its back surface hollowed or recessed slightly 40 and/or provided with edge ridges such as 19 and 20 to effect a tight seal with the faces of the panels. The adjacent ends of panels 8 and 16 are retained in place similarly by a batten strip 21 which is a duplicate of the batten strip 17.

As hereinbefore stated, the ends of the panels such as 7 and 8 are spaced from the flanges such as 3 and 4 of the angle bars by the heads and nuts of the bolts such as 6, and this space is filled with a calking compound indicated at 22 which 50 preferably is of non-setting character and applied in such quantity as will slightly more than fill such space and extrude therefrom slightly beyond the face of each panel so that, when the batten strip is drawn by nailing into tight contact with 55

said panels, the extruded compound will thoroughly seal the joint formed by the panels, the angle bar flanges and said batten strip against entry of moisture particularly into the end of the 5 panels. The calking compound may be trowelled over the bolted angle bar flanges prior to placement of the panel ends in place and hence it is also possible to have such compound applied similarly over the surface of the rear flanges such 10 as 1 and 2 to additionally seal the joint therewith of the rear surfaces of the panels. The calking compound may comprise any of the well known commercial substances used for such purposes, or 15 bituminous compounds, asbestos compounds, suitable cements, etc. any of which will serve the intended purpose and possibly additionally be fire resistant.

The separating strip such as 5 may be any suitable nail-retaining member preferably treated 20 to be moisture repellent and possibly fire resistant. While various such members are known, specific examples are (1) asphalt saturated "Celotex" which preferably has a density of about 0.26 and is saturated to the extent of approximately 25 150-200% of its weight with an asphalt or asphaltic substance or compound of about 140° melting point, (2) a similarly saturated asbestos sheet which naturally would be of appreciably higher density, (3) or any other type of 30 fiber board as a basic material for similar saturation. The fiber board comprises a porous mat for retaining the asphaltic substance and serves to reinforce and strengthen said substance and to almost completely (at least under ordinary 35 conditions) retard the natural flow characteristics thereof.

As hereinbefore stated, the vertical studs or supporting units are preferably formed by bolting together a pair of metallic angle bars, but 40 other means may be found expedient for such securing. For example they may be riveted together, or secured by welding, but in such cases it will be advisable to insert spacers between the facing flanges such as 3 and 4 in order 45 to maintain proper spacing during the securing. Such spacers may be relatively short blocks, or a relatively narrow strip disposed in the plane of the back flanges such as 1 and 2 and pre-welded possibly to one of said flanges. 50 If blocks or strips are employed and to be left permanently in the assembled stud, they should be designed so as to permit entry and retention of the anchoring strip 5 between the facing flanges 3 and 4. In all forms of assemblage, the 55 anchoring strip should be firmly clamped between the facing flanges, preferably under considerable pressure.

When securing means other than bolts are employed, bosses or the like should be provided 60 on the flanges 3 and 4 so that the spaces 22 will be definitely provided between the end of the inserted panel and the flange of the stud, such bosses being the equivalent of the bolt heads and nuts shown in the drawing. These bosses could 65 be the heads of the rivets when riveting was employed for assembling the studs, but when welding was employed, it would be feasible to weld small blocks of metal at spaced intervals to provide said bosses.

70 Whereas in the drawing the finished side of the partition contains the batten strips, it is not to be inferred that the opposite side cannot be given a finished appearance. In other words, the metal stud may constitute the thickness of the 75 partition, wherefore each side would be exposed

and therefore susceptible of finishing. Hence, the exposed flanges such as 1 and 2 may be suitably decorated as by painting or other coating, and the surface of the panels may be likewise treated. On the other hand, different treatment may be given such for example as applying any of the fiber and/or plaster boards to be found on the market and which may be nailed or otherwise secured to the anchoring strips 5 and/or to the panels themselves. 10

It is obvious that those skilled in the art may vary the details of construction and arrangements of parts without departing from the spirit of this invention and therefore it is desired not to be limited to the exact foregoing disclosure 15 except as may be demanded by the claims.

What is claimed is:

1. Partition construction comprising angled metallic supporting members; an asphalt impregnated anchoring strip carried by the supporting members; partition panels having their ends fitted within the angles of said members; and a batten strip overlapping the adjoining ends of said panels, said batten strip secured to said asphalt impregnated anchoring strip, whereby 25 a moisture repellent joint construction for the partition construction is formed.

2. Partition construction comprising angled metallic supporting members; an anchoring strip comprising asphalt impregnated felted fiber board carried by the supporting members; partition panels having their ends fitted within the angles of said members; and a batten strip overlapping the adjoining ends of said panels, said 30 batten strip secured to said asphalt impregnated 35 felted fiber board by a device adapted to penetrate the latter.

3. Partition construction comprising angled metallic supporting members; an asphalt saturated anchoring strip carried by the supporting 40 members; partition panels having their ends fitted within the angles of said members; calking compound sealing the ends of said panels in the angles of said members; and a batten strip overlapping the adjoining ends of said panels, said 45 batten strip secured to said anchoring strip and covering the sealed ends of said panels, whereby a moisture repellent joint construction for the partition construction is formed.

4. Partition construction comprising angled 50 metallic supporting members; an anchoring strip comprising asphalt impregnated felted fiber board secured to the supporting members, said 55 securing providing projections constituting spacers; partition panels having their ends fitted within the angles of said members and substantially contacting said projections to provide a space adjacent said ends; calking compound filling said space and sealing the panel ends; and a batten strip overlapping the adjoining ends of 60 said panels, said batten strip secured to said asphalt impregnated felted fiber board and placing said compound under pressure in said space.

5. Partition construction comprising angled 65 metallic supporting members; an anchoring strip of relatively low density comprising felted fiber board treated to be moisture repellent carried by the supporting members; partition panels having their ends fitted within the angles of said members; and a batten strip overlapping the adjoining 70 ends of said panels, said batten strip secured to said anchoring strip and sealing the latter against moisture penetration.

6. Partition construction comprising a plurality of panels and a plurality of supporting units 75

therefor, each supporting unit comprising a pair of metallic members each having flanges establishing an angle with the ends of the panels disposed in said angles, each pair of metallic members secured together with an asphalt impregnated anchoring strip interposed between two adjacent flanges thereof, and a batten strip disposed across the ends of the said two adjacent flanges and overlapping the ends of two adjacent panels, said batten strip secured to said asphalt impregnated anchoring strip and holding said panel ends in position by contact therewith at the edge portions only of said batten strip, whereby a moisture repellent joint construction for the partition construction is formed.

7. Partition construction comprising a plurality of panels and a plurality of supporting units therefor, each supporting units comprising a pair of metallic members each having flanges establishing an angle with the ends of the panels disposed in said angles, each pair of metallic members secured together with an asphalt impregnated anchoring strip interposed between two adjacent flanges thereof, calking compound disposed between the ends of said panels and the said two adjacent flanges to form a seal for the panel ends, and a batten strip disposed across the ends of the said two adjacent flanges and overlapping the ends of two adjacent panels, said batten strip secured to said asphalt impregnated anchoring strip and holding said panel ends in position by contact therewith at the edge portions only of said batten strip, said batten strip establishing a pressure upon said compound to insure said seal, whereby a moisture repellent joint con-

struction for the partition construction is formed.

8. In a partition construction comprising a plurality of partition panels, a nailing stud comprising a pair of spaced elongated members and adapted for the erection of the partition panels thereon, a strip of nail-holding composition comprising fiber and asphalt positioned between the spaced elongated members, and means tightly securing the elongated members and strip of nail-holding composition in assembled relation, whereby a moisture repellent joint construction for the partition construction is formed.

9. In a partition construction comprising a plurality of partition panels, a nailing stud comprising a pair of spaced elongated members and adapted for the erection of contiguous partition panels thereon, a strip of nail-holding composition comprising fiber board saturated with asphaltic material, said strip positioned between the spaced elongated members, and means tightly securing the elongated members and strip of nail-holding composition in assembled relation, whereby a moisture repellent joint construction between contiguous partition panels is formed.

10. As an article of manufacture, a nailing stud comprising a pair of spaced elongated metallic members, a strip of nail-holding composition comprising fiber board saturated with asphaltic material, said strip positioned between the spaced elongated members, and means tightly securing the elongated members and strip of nail-holding composition in assembled relation, whereby said nailing stud is adapted to form a moisture repellent joint construction.
